UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,084,066.

Specification of Letters Patent.

Patented Jan. 13, 1914.

Application filed May 8, 1911. Serial No. 625,669.

To all whom it may concern:

Be it known that I, MATTHIAS BROCK, a citizen of the United States, residing at Boston, in the county of Suffolk and State of Massachusetts, have invented certain Improvements in Lasting-Machines, of which the following description, in connection with the accompanying drawings, is a specification, like reference characters on the drawings indicating like parts in the several figures.

This invention relates to shoe machinery and especially to lasting machines and is of particular utility when embodied in a lasting machine of a type illustrated in the United States Letters Patent to Grandy No. 552,834, dated January 7, 1896, although I contemplate the utilization of my improvements in any field for which they are adapted by their nature.

An important object of my invention is to provide improved power actuated mechanism to accomplish certain arduous operations necessary in the lasting of shoes, which are usually accomplished by hand with undue demands upon the strength and attention of the operator, notably the stretching and crimping of the upper material over the toe and heel portions of the last.

Another important object of my invention is to provide mechanism for the manual actuation of these same devices when for any reason it is not desired to use the power mechanism, and a cognate and highly important object of my invention is to relate these manually operated devices to the power actuated mechanism in such fashion that the manually operated device may be used as means to control the operation of the power mechanism, with the result that whether the operator is using the power mechanism or performing the operations manually, he will in each instance operate the same controlling devices and will thus avoid the disturbing factor of a change from a familiar to an unfamiliar set of controlling devices.

A feature of the invention consists in the provision, in connection with wipers which may be operated to work the upper into lasted position, of means for moving relatively the wipers and the last perpendicular to the plane of the last bottom by power to compress the upper against the face of the

toe portion of the last, together with means for augmenting manually the power compression of the upper. In the mechanism herein shown and described as embodying this feature of the invention, means is provided for actuating the wipers in a direction perpendicular to the face of the last bottom for the purpose of applying compacting pressure to the overlasted upper materials and means for controlling the upward movement of the wipers and their return upon the shoe with upper compacting force, the controlling means being so constructed and arranged that after the power means has been set in operation said controlling means becomes effective upon further movement for supplementally operating the wipers to further compact the upper materials manually. Furthermore the power mechanism may come to rest with the work under pressure and when the mechanism is restarted means may be provided for relieving automatically the pressure on the overlaid upper and for then backing off the wiper. In this way the outward drag caused by retracting the wiper, while it is still pressing vertically upon the upper materials, is avoided.

Another important feature of the invention consists in means for effecting power actuation of the wipers to advance and close them over the last bottom and controlling means, for example, a hand lever, is operatively connected with the power means, the controlling means being also arranged to become effective during a portion of its operative movement to actuate the lasting devices manually. This arrangement may involve a lost motion connection of the lever to the wipers to effect actuation of the wipers manually and the power means may be in operation during the lost motion between the controlling lever and the wipers.

As a further feature of the invention the controlling lever may be employed either to augment or to counteract manually the power actuation of the lasting devices. Furthermore the controlling lever is arranged to set the power means in operation and, upon continued movement of the lever in the same direction, to actuate the wipers manually. This manual operation of the wipers is preferably in addition to or supplemental to their power actuation and is for the pur-

pose of increasing the effect of the power actuation of the lasting devices.

A further feature of the invention consists in means for jacking the shoe by power, the means for controlling the power actuation of the jacking means being arranged to become operative upon continued movement thereof to actuate the jacking devices manually. This feature of the invention is shown and described by way of illustration as applied to the toe rest of the lasting machine, a manually operated lever being provided for controlling the application of power to the toe rest, said lever being arranged for continued movement in the same direction to actuate the jacking device manually.

In its preferred form my invention provides fluid-pressure mechanism to afford the means for actuating by power the several devices for performing the operations forming the subject matter of this application, and handles and treadles are provided in appropriate places for operation by the hands and feet of the operator, these handles and treadles being connected with and arranged to operate valves governing the application of the fluid-pressure to cylinders constructed and arranged to actuate the lasting devices, including in that expression broadly any device in the machine thus actuated. In numerous respects, however, my invention is not limited to the nature of the power operating mechanism but is broad enough to include, and the claims are to be so interpreted whenever their terms permit of such a construction, any power operated mechanism for causing the lasting instrumentalities to do their work.

Among still other notable features of my invention may be mentioned the provision of means by which the fluid in the power cylinders is utilized as a check or retarding medium for certain portions of the mechanism including a spring in which power is stored, particularly for use in the operation of the tacking mechanism, this check operating in place of, or as an auxiliary to, the fluid check heretofore provided by me for lasting machines of this type, and which is illustrated and described in United States Letters Patent 1,018,477, granted to me Feb. 27, 1912.

I have provided also for means by which the power exerted by the fluid under pressure may be in certain operations offset in part or in whole manually, so that in such an operation as that of stretching the upper material over the toe, for example, the operator can exert a countervailing action in opposition to the fluid pressure, thus affording the possibility of very delicate gradation of the force applied to the material at various stages in its treatment, the latter purpose, in general, being an outstanding

characteristic of the respective objects herein enumerated.

The various features of my invention will be illustrated and described fully in the accompanying drawings and specification, and 70 pointed out in the claims.

In the drawings, Figure 1 is a view in front elevation of a lasting machine in the construction of which my invention has been embodied; Fig. 2 is a fragmentary detail view in plan, upon an enlarged scale, of the toe lasting mechanism of the machine shown in Fig. 1; Fig. 3 is a view in vertical section on the line $\alpha^3-\alpha^3$, Fig. 1, looking from right to left, parts being shown in elevation, and other parts omitted or broken away for the sake of clearness in illustration; and Fig. 4 is a perspective view of parts shown in Fig. 3.

In the embodiment of my invention selected for illustration and description, to enable ready and complete understanding of my improvements, the part designated by the reference numeral 1 is the bed of a lasting machine, which may be of any suitable construction and as one convenient form of such construction is provided with a base or frame comprising standards 2 and cross-pieces 21, the bed serving as a support for heads, blocks or frames 3 and 4 upon which are supported the lasting devices for the toe and heel parts respectively; the bed supporting also the "jacking" devices comprising the toe support 5 and heel post 6, all of which may be of any suitable construction, 95 and which may conveniently be, and preferably are, substantially as in said Grandy patent.

In the instance illustrated, the toe-lasting devices comprise wipers 8 and 10 mounted upon carrier members 12 and 14 having slots 16 and 18 respectively to receive bolts 20 which serve to give the proper direction to the wiper device 8 and 10 in their wiping action when actuated thereto by suitable means which in the instance illustrated comprises a pair of links 24 connected to a bar 26, the links being preferably connected pivotally to the carriers 12 and 14 respectively as at 28, and the toe lasting devices 115 in combination being supported preferably by a suitable cradle 30, all of which may be as illustrated and described in the aforesaid Patent No. 552,834. As disclosed in said patent the cradle 30 may conveniently 120 be mounted pivotally as at 32 (see Fig. 1) to permit rocking movement of the cradle and the toe lasting devices about a horizontal axis extending transversely of the machine from front to rear under the control of a suitable device such as the crank-handle 34 operating a screw 36 having a suitable bearing on a slide or table 38 which forms part of the head-block 3 carrying the toe lasting devices, this slide is preferably con- 130

structured and arranged to move bodily upon the head 3 along the longitudinal axis of the machine, under the control of a suitable device such as the screw shaft 40 and hand wheel 42, the former being mounted in a suitable bearing block 44. I prefer to provide also for the usual lateral oscillation or tilting movement of the lasting devices to accommodate the "roll" of the last, and for this purpose the lasting devices are shown as mounted upon a sleeve 57 (see Fig. 2) which extends preferably along the longitudinal axis of the machine, the sleeve 57 deriving its support from bed blocks 52 secured by suitable means such as the bolts 54 upon the cradle 30, and to regulate this tilting movement positively I have shown a screw shaft 56 engaged with a collar 58 and actuated by a handle 60. The above parts also are substantially as shown and described in said Patent No. 552,834, the rod 50 being connected to the equalizing bar 26, and serving when actuated co-axially by suitable means to force the equalizing bar forward and drive the wipers into shearing engagement with the toe of the shoe, in a manner well understood to those skilled in the art, and which need not be detailed herein as it constitutes no part of my present invention.

In accordance with my invention, I provide suitable power mechanism to actuate the wipers 8 and 10, and such actuating means may be of any suitable construction. As one convenient form of device for this purpose, I have shown a fluid pressure cylinder 70, constructed and arranged to receive a piston 72 mounted upon the rod 50 near its end, the cylinder being mounted upon a suitable support such as the yoke 74 bolted at 76 and 78 to the bed block of the cradle with which the cylinder may turn when the cradle is oscillated laterally by the handle 60, the cylinder rising and falling also with the cradle in its movements about the horizontal axis 32 under the action of the handle 34, already described.

To operate the cylinder 70 any suitable medium may be employed, and I have shown as one convenient form of operating means an inlet tube 80 leading from the cylinder to a suitable source of fluid under pressure such as the stand pipe 82, provided with a weighted piston 84, an outlet or return pipe 86 being also provided preferably leading from the cylinder 70 to a pump 88 driven by a motor 90 from which the fluid is forced through the conduit 92 and stored again under the pressure in the stand pipe 82.

To control the operation of the piston 72 in the cylinder 70, by regulation of the introduction to the cylinder of the fluid under pressure any suitable means may be provided, and as one convenient form of device

for this purpose, I have shown a 3-way valve 94 operated by a hand lever 96, and in accordance with an important feature of my invention this handle 96 may be utilized for the manual actuation of the rod 50, when for any reason it is desired to omit or to supplement the power actuation of the lasting devices. For this purpose a slotted rod 98 is shown connecting by headed stud 99 the hand lever 96 with a bolt 100 on the rod 50, this slot connection permitting sufficient play of the handle 96 to operate the valve 94 ordinarily before the slotted end of rod 98 is positively engaged by the stud 99 for manual actuation of the rod 50. If for any reason manual operation is to be substituted for operation by fluid pressure or is to be used to supplement the power operation the movement of the handle 96 continuously in the ordinary direction of its movement for operation of the valve 94 will result in manual actuation of the toe-lasting devices 8 and 10. If found desirable, suitable means may be provided to move the rod 50 in reverse direction for the purpose of opening the toe-wiping devices, and any suitable means may be provided for this purpose, one convenient form of such means being constituted by the spring 102, Fig. 2, within the cylinder 70, and if desired the bolt and slot connection 98-99 may be so arranged that when the handle 96 is reversed, the same movement which closes the inlet and opens the outlet will, if continued, enable the operator to withdraw the rod 50 positively leftwardly and open the wipers 8 and 10.

Similarly, in accordance with my invention, the actuation of the heel lasting devices carried by the head 4 may be provided for by running an inlet conduit 104 and an outlet conduit 106 from the stand pipe 82 and pump 88 respectively to a cylinder 170 having a piston 172 connected operatively with a rod 150 which in turn is connected actuatively with heel wiping devices 108, the latter being mounted upon a cradle 130, mounted upon a transverse horizontal axis 132 upon the head 4, a hand crank 134 serving to rock the plane of the wipers about the axis 132 while a hand crank 160 serves to tilt the cradle 130 and heel wipers 108 about the longitudinal axis of the rod 150. The reference numeral 7 designates a table mounted pivotally at 9 upon the bed 1, and swinging at its rear end upon a track 11 the table carrying the head 4 upon suitable ways 13 along which the head 4 may be moved by the hand-wheel 15. The reference numeral 17 designates a hand-crank 125 to adjust limiting stops for the swinging movements of the table.

The parts described in the foregoing paragraph may be, and preferably are, all substantially the same in construction and oper-

ation as similar parts described in my above mentioned Patent No. 1,018,477, with the exception of the fluid pressure cylinder and its connections, for the control of which I have shown a handle 196 operating a valve, similar in construction and operation to the handle 96 and valve 94 already described herein with respect to the toe lasting devices.

The numeral 203 designates a spring to return the rod 150 and wipers 108 to their normally open, inoperative position.

The handle 196 may be used to actuate the rod 150 and wipers 108 manually in a fashion similar to that described with reference 15 to the valve lever 96.

In a machine of this character it is customary to provide for raising and lowering the heel post 6, and suitable mechanism may be provided if desired for accomplishing 20 such movement by fluid pressure or power, but as very little power is required for this purpose, I have not shown fluid pressure mechanism to accomplish the same and have merely indicated the machine illustrated as 25 provided with one convenient form of treadle 61 for the above purpose, the lever being mounted upon a stud 63 on one of the frame uprights 2, and having a connecting rod 65 running to a bell-crank lever 67 carried upon a shaft 69 in brackets 71 depending from the bed 1, suitable connections, not shown, leading from the bell crank 67 to the heel post 6, preferably as detailed in my aforesaid Patent No. 1,018,477, the specific 30 form of mechanism for raising and lowering the heel post forming no part of my present invention. So, also, the raising and lowering of the toe support 5 may be accomplished by any suitable mechanism, such as that 35 illustrated in full detail and described at length in my aforesaid Patent No. 1,018,477, and which need not be illustrated in detail in the present application, in which it will be sufficient for a proper understanding 40 of my present invention to note that the mechanism for raising and lowering the toe support includes a rod 81 which, as may be seen most readily by reference to Fig. 3 is connected at 83 with a disk 85, carrying a 45 pawl 87 to be engaged with the teeth of a ratchet wheel 89 mounted rotatably upon a cam shaft 91 carried in suitable bearings upon the bed 1, and this cam shaft 91 when rotated serves to perform certain operations 50 detailed in my aforesaid patent, including the raising of the toe support 5. In accordance with an important feature of my invention, I prefer to actuate the ratchet wheel 89, pawl 87 and rod 81 by power, as the rod 81 55 is operated frequently and it is desirable to relieve the operator ordinarily of the necessity for applying manually to it the power necessary to accomplish its actuation.

Any suitable power device may be provided to actuate the rod 81, and as one con-

venient form of device for this purpose I have shown the rod as having an extension 93 provided with a piston 95 fitted within a cylinder 97 provided with an inlet pipe 99, and an outlet pipe 101, connected respectively with the stand pipe 82 and pump 88, heretofore described. To control the operation of the fluid pressure cylinder 97 and rod 93 I have shown, as one convenient form of means, a 3-way valve 127 operated by a crank 105 having studs *b*, *c*, arranged in the cam slot *a* of an operating slide 129 the lower end of which is connected to a treadle 109, depression of the treadle serving to open the valve 127 and admit fluid under pressure to the cylinder 97, a spring 111 serving to close the valve, by raising the valve operating slide 129 and treadle 109 when the latter is released. In order to permit manual actuation of the rod 81, in accordance with my invention, any suitable device may be provided, and as one convenient form of such mechanism, I have shown the treadle 109 as mounted upon a stud 113 carried by the frame member 33, the treadle 109 having an arm 115 extending into position to engage at times with a stud 117 carried by a lever 119 which is also fulcrumed upon the stud 113, the lever 119 being connected at 121 with a slide 123 which is also connected at 125 with the rods 93 and 81. The arm 115 is so proportioned that when the treadle 109 is depressed, ordinarily, the valve 127 will be opened and fluid pressure will be released to operate the piston 95 and rods 93 and 81, before the operator exerts any considerable manual pressure upon the lever 119 through the arm 115 and stud 117. If for any reason the fluid pressure is not in operation a simple continued downward pressure by the operator upon the treadle 109 will engage the arm 115 with the stud 117 and will operate the lever 119 to draw down the slide 123 and rods 93 and 81, thus operating the ratchet wheel 89. A spring 135 may be provided to return the rod 81 to its normal position shown in Fig. 3.

The lever 119 is utilized to wind up a spring 146 to store energy therein for the operation of the tack feeding mechanism 115 of a hand-tacker used in the lasting operation, and which I will now describe briefly, referring to my aforesaid Patent No. 1,018,477 for a more detailed description of this mechanism, the details of which form 120 no part of my present invention. For purposes of my present description it is sufficient to say that when the lever 119 is operated it forces upward a rack-bar 142 through the medium of a link 140, and rotates a shaft 144 to wind up the spring 146, the latter operating by suitable connections 125 through a belt 162 to rotate the tack feeding mechanism 164 by which the tacks are passed to the hand tacking device 168, and 130

when the lever 119 is released the descent of the rack-bar 142 under the action of the spring 146 is retarded by suitable means which in the instance illustrated may comprise the fluid above the piston 95 in the cylinder 97, together with the weight of the piston rod 93, connecting rod 81 and slide 123. At times when the fluid is not present in the cylinder 97 I may, as an auxiliary check for the rack-bar 142, retain the checking device illustrated in Fig. 3, and described more at length in my aforesaid patent, as comprising a piston 151 operating in a cylinder 152 containing fluid, which may be introduced into a reservoir 154 and controlled by a thumb-screw 155. When there is fluid present in the cylinder 97, the thumb-screw 155 may be opened to permit free operation of the piston 151 and rack-bar 142.

In accordance with another important feature of my invention the mechanism for raising and lowering the head 3 may, and preferably will, be actuated by power to accomplish the operation of stretching the upper material over the toe, and for this purpose I have shown the connecting rod 250 by which this is accomplished as provided with a piston 272 entering a cylinder 270 carried by one of the frame uprights 2, this cylinder having an inlet conduit 280 and an outlet conduit 286 leading from the standpipe 82 and to the pump 88 respectively, a three-way valve 294 serving to regulate the flow of fluid, under the control of suitable means such as the crank 296, actuated by a rod 298 running to a treadle 299, which may and, in accordance with a valuable feature of my invention, preferably will have a slotted rod 302 connecting by headed stud 312 the treadle with the member 250 for manual actuation of the latter by the continued movement of the treadle. By adjustment of the nuts 300 on the rod 298, the operation of the valve 294 can be timed in advance of the upward actuation of the link 302 by the treadle 299, so that resort need only be had to manual uplift of the head 3 in the absence of or in addition to fluid under pressure. A spring 303 may be provided to return the parts to the normal position shown in Fig. 1. The treadle 299 and slotted rod 302 may serve also to enable the operator to exert a more sensitive check upon the power applied to working upon the shoe, for by bearing down with his heel upon the heel of the treadle 299 the operator can counteract the fluid pressure.

Having illustrated and described my invention thus fully, and suitable means for carrying the same into effect, I wish it to be understood that I do not limit myself to the specific construction and materials selected for illustration and description by way of example, nor in general do I limit

myself otherwise than as set forth in the claims read in connection with this specification.

I claim—

1. A lasting machine having, in combination, end embracing wipers arranged to advance and close over a last bottom, means for manipulating the wipers to work the upper into lasted position, power means for relatively moving the wipers and the last perpendicularly to the plane of the last bottom to compress the upper against the bottom face of the toe portion of the last, and means for augmenting manually the power compression of the upper. 70

2. A lasting machine having, in combination, end embracing wipers arranged to advance and close over a last bottom, a hand lever fulcrumed to a fixed part of the machine and connected to said wipers, fluid pressure operating mechanism including a valve also connected with the wipers, and valve controlling means for said mechanism arranged to be operated by said hand lever. 80

3. A lasting machine having, in combination, end embracing wipers arranged to advance and close over a last bottom, a hand lever fulcrumed to a fixed part of the machine and having a lost motion connection with the wipers, and a power operating mechanism for the wipers arranged to be started by said lever during the lost motion between it and the wipers. 90

4. A lasting machine having, in combination, end embracing wipers arranged to advance and close over a last bottom, a hand lever fulcrumed to a fixed part of the machine and having a lost motion connection with the wipers, a fluid pressure actuating mechanism for the wipers having a valve which is arranged to be operated by said lever during the lost motion between the lever and the wipers. 100

5. A lasting machine having, in combination, end embracing wipers, means to advance the wipers over the last bottom to do their work, automatic means to effect compression of the upper between the wipers and the last bottom, means for increasing manually the pressure applied by the wipers, and means for automatically retracting the wipers from the shoe when the compressive pressure is discontinued. 110

6. A lasting machine having, in combination, end embracing wipers, power means to advance the wipers over the last bottom, power means to depress the wipers relatively to the last bottom and a spring operating automatically to retract the wipers when the advancing force is discontinued. 120

7. In a machine of the class described, lasting apparatus comprising lasting devices, power-actuated operating mechanism therefor, manually operated devices for controlling application of power to said power 130.

- mechanism, and connections permitting manual actuation of said lasting devices by said controlling devices.
8. In a machine of the class described, 5 lasting apparatus comprising lasting devices, power-actuated operating mechanism therefor, manually operated controlling devices for said power mechanism, and connections permitting manual actuation of said lasting devices by said controlling devices when moved in the direction of the controlling motion.
9. In a machine of the class described, 10 lasting apparatus comprising lasting devices, fluid-pressure actuating mechanism therefor, and a manually actuated member arranged to permit operation progressively to a position of control for said fluid-pressure and to a position of positive actuation of said lasting devices.
10. In a machine of the class described, 15 lasting apparatus comprising lasting devices, a rod connected operatively with said devices, a fluid-pressure cylinder having a piston connected operatively with said rod, a valve to control said fluid, and a lever for operating said valve to actuate the lasting devices by power and connections between said lever and the lasting devices for actuation of said devices manually.
11. In a machine of the class described, 20 lasting apparatus comprising lasting devices, and actuating mechanism including cylinders, pistons therefor connected operatively with said lasting devices, manually 25 operated means for controlling the application to said cylinders of fluid under pressure, and operating connections between said controlling means and the lasting devices whereby said lasting devices and the 30 controlling means may be actuated manually.
12. In a machine of the class described, 35 lasting apparatus comprising lasting devices, and actuating mechanism including cylinders, pistons therefor connected operatively with said lasting devices, and manually operated means for controlling the application to said cylinders of fluid under 40 pressure, and connections whereby said lasting devices may be actuated manually by said controlling means.
13. In a machine of the class described, 45 lasting apparatus comprising lasting devices, fluid-pressure actuating mechanism therefor, and a manually actuated member arranged to be operated to control the application of fluid to said mechanism, also to 50 countervail manually the power exerted by said mechanism, and to actuate said lasting devices manually.
14. In a machine of the class described, 55 lasting apparatus, comprising lasting devices, a fluid-pressure cylinder connected 60 with said lasting devices, a controlling valve

- for said cylinder, a treadle connected with said lasting devices for manual actuation thereof, and connected with, and to operate said valve, said treadle having a toe portion to operate said valve and lasting devices, and a heel portion capable of operation to countervail the operative action of 65 said cylinder.
15. In a machine of the class described, 70 lasting apparatus comprising a head provided with lasting devices, and power operating mechanisms to move vertically said head bodily upwardly with said lasting devices and means for insuring the return of 75 said head with upper compressing force.
16. In a machine of the class described, 80 lasting apparatus comprising a head provided with lasting devices, and power operating mechanism to move vertically said head bodily with said lasting devices and to 85 operate said lasting devices upon said head.
17. In a machine of the class described, 90 lasting apparatus comprising a head provided with lasting devices, and fluid-pressure mechanism to move said head bodily 95 with said lasting devices and to operate said lasting devices upon said head, said mechanism including a fluid-pressure cylinder upon said head, and movable relatively thereto, with said lasting devices.
18. In a machine of the class described, 100 lasting apparatus comprising a bed, and a head mounted slidably thereupon, said head including a cradle mounted on said head to rock about a transverse axis, lasting devices carried by said head and capable of oscillation about a longitudinal axis thereof, and a fluid-pressure cylinder connected directly with said lasting devices.
19. In a machine of the class described, 105 lasting apparatus comprising a bed, and a head mounted slidably thereupon, said head including a cradle mounted on said head to rock about a transverse axis, lasting devices carried by said head and capable of oscillation about a longitudinal axis 110 thereof, and a fluid-pressure cylinder connected with said lasting devices and movable as a unitary structure therewith.
20. In a machine of the class described, 115 lasting apparatus comprising toe-lasting devices, heel-lasting devices, fluid-pressure mechanism to operate said devices, and means for separately controlling the fluid operated toe and heel-lasting devices.
21. A machine of the class described, having, in combination, means for operating on a shoe, a lever for operating said means by hand, mechanism to operate said means by power, and connections whereby said 120 lever first releases the power mechanism and upon further manipulation becomes effective for supplementally operating said means manually.
22. In a machine of the class described, 125 130

lasting apparatus comprising a jacking device, mechanism arranged to be controlled manually to actuate said device by power, and mechanism arranged to become operative upon continued movement of the controlling means to actuate said jacking device manually.

23. In a machine of the class described, lasting apparatus comprising a jacking device, controlling mechanism arranged to be operated manually to actuate said device by power, and mechanism operated by continued movement of said controlling mechanism in the same direction to actuate said jacking device manually.

24. In a machine of the class described, lasting apparatus comprising a jacking device, a tacking appliance, including a power storage member, mechanism serving both to operate said jacking device and store power in said member, and a fluid-pressure cylinder to actuate said mechanism.

25. In a machine of the class described, lasting apparatus comprising a jacking device, a tacking appliance including a power storage member, mechanism serving both to operate said jacking device and store power in said member, a fluid-pressure cylinder to actuate said mechanism, and a manually operated controlling device for said cylinder, said controlling device constituting an auxiliary actuator for said mechanism.

26. In a machine of the class described, lasting apparatus comprising tacking mechanism, including a spring in which power may be stored, a fluid-pressure cylinder connected with said spring for tensioning the spring by power, and serving also as a check upon the unwinding of said spring, and means to regulate said checking action.

27. In a machine of the class described, lasting apparatus comprising tacking mechanism, including a spring in which power may be stored, a fluid-pressure cylinder connected with said spring, and serving also as a check upon the unwinding of said spring, means to regulate said checking action, a manually actuated member to wind up said spring, and an auxiliary fluid check therefor.

28. In a machine of the class described, lasting apparatus comprising a frame, tacking mechanism, a lever fulcrumed on said frame and connected with said tacking mechanism, a fluid pressure cylinder connected with said lever, a treadle fulcrumed adjacent to said lever and having an arm to be engaged with a part thereof, and a controlling valve for said cylinder connected with said treadle for actuation thereby prior to operative engagement of said arm with said lever.

29. In a machine of the class described, lasting apparatus comprising jacking mechanism including an actuating rod, tacking mechanism including an actuating lever, a fluid-pressure cylinder having an inlet valve,

and outlet valve, a piston, and a piston-rod connected operatively with said actuating-rod, a plunger connecting said piston and lever, and provided with a plurality of stops to operate said outlet valve, a treadle fulcrumed adjacent to said lever and having an arm to be engaged with a part of said lever, a link connecting said treadle operatively with said inlet valve, a spring tending normally to hold said inlet valve open and said treadle raised, and a spring tending normally to return said lever, plunger and piston to position for actuation by said fluid-pressure.

30. In a machine for working an upper into position to be fastened by tacks, fluid-pressure actuating means for jacking the shoe combined with mechanism operatively connected with the jacking means to arrange and deliver the fastening tacks.

31. In a machine for working an upper into position to be fastened by tacks, means for jacking the shoe, mechanism for arranging and delivering the fastening tacks, and fluid-pressure actuating mechanism for operating the jacking means and setting into operation a slow moving actuator for the tack supplying mechanism, combined with said slow moving actuator.

32. In a machine for working an upper into position to be fastened by tacks, shoe jacking means, means for arranging and delivering the tacks, a spring for actuating said tack supplying means, and fluid-pressure mechanism arranged to actuate the jacking means and to tension said spring and arranged to retard the reaction of the spring to insure a slow actuation of the tack supplying mechanism after the actuation of the jacking mechanism.

33. A lasting machine having, in combination, manual operating mechanism, fluid pressure operating mechanism, devices for controlling these mechanisms, said mechanisms and devices being constructed and arranged so that when it is desired to operate parts of said machine the initial movement of a controlling device in the direction of manual actuation of said parts renders the fluid pressure mechanism operative for the actuation of said parts, and that supplemental actuation of said controlling device will bring the manually operated mechanism into operation, said controlling device and manual operating mechanism being capable of co-action to operate said parts without resort to said fluid pressure mechanism.

34. A lasting machine, having, in combination, end embracing wipers, a lever for operating the wipers by hand, means to advance the wipers by power, and means whereby said lever first releases the power means and upon further manipulation becomes effective for advancing the wipers manually.

35. A lasting machine, having in combination, end embracing wipers, fluid pressure operating means for the wipers, a hand lever for setting said fluid pressure means into 5 operation when the hand lever is moved in one direction, additional means between the lever and the wipers for advancing the wipers manually, said last-named means becoming effective upon continuation of the 10 movement of the lever in the same direction.

36. A machine for conforming an upper to a last having, in combination with a shoe support, end embracing wipers, power mechanism to cause the wipers to lay the margin 15 of the upper materials over and hard down upon the last bottom and come to rest with the work under pressure, means for backing off the wipers from the shoe bottom when the mechanism is restarted, and means for 20 automatically relieving pressure on the overlaid upper materials before the wipers are backed off so that outward drag of the wipers tending to displace the overlaid materials is avoided.

37. In a machine of the class described, the combination with lasting devices, means for actuating the lasting devices by power, a manually actuated member having operative connections with the power means to 30 control the operation thereof and arranged to become effective during the latter portion of its operative movement to actuate the lasting devices manually.

38. In a machine of the class described,

the combination of lasting devices, means 35 for actuating said devices by power, a member arranged to be operated manually and connected with the power means to control the application of power to said lasting devices, said member being also adapted to be 40 operated to counteract or to augment manually the power actuation of the lasting devices.

39. A lasting machine, having in combination, end embracing wipers, power means 45 for operating the wipers, a hand lever for setting said power means into operation when the hand lever is moved in one direction, and additional means between the lever and the wipers for advancing the wipers 50 manually, said last-named means becoming effective upon continuation of the movement of the lever in the same direction as that required for setting the power means into operation.

40. In a machine of the class described, lasting apparatus comprising toe embracing wipers, heel embracing wipers, power operating mechanism to operate said wipers, and means for separately controlling said power 60 operated toe and heel embracing wipers.

In testimony whereof I have signed my name to this specification in the presence of two subscribing witnesses.

MATTHIAS BROCK.

Witnesses:

ARTHUR L. RUSSELL,
HERBERT W. KENWAY.
